UNITED STATES PATENT OFFICE.

JAMES C. CAVILL AND GEORGE F. LEHBERGER, OF NEW CASTLE, PENNSYLVANIA.

ROLL-POLISHING DEVICE.

1,018,163.

Specification of Letters Patent. Patented Feb. 20, 1912.

Application filed October 9, 1911. Serial No. 653,980.

To all whom it may concern:

Be it known that we, JAMES C. CAVILL and GEORGE F. LEHBERGER, citizens of the United States, residing at New Castle, in the county of Lawrence and State of Pennsylvania, have invented a new and useful Roll-Polishing Device, of which the following is a specification.

This invention relates to certain new and useful improvements in roll polishers and relates particularly to a polisher for metal rolls such as are used in tin mills, sheet mills, plate mills or the like in which sheets, plates, bars, or the like are rolled.

15 The invention has for its main object to provide a polisher which can be employed for polishing the rolls without interfering in any manner with the operation of the rolls whereby the polishing may be effected while 20 the mill is in operation.

A further object of the invention is to provide a device which can be readily and quickly placed in operation at any time desired by the workmen at the rolls, and which, 25 when in operation, causes the polishing block to travel from end to end of the rolls in both directions until thrown out of operation.

With the above and other objects in view, 30 the invention consists in the novel construction of the device as will be hereinafter specifically described, and then particularly claimed.

In describing the invention in detail, reference will be had to the accompanying drawings forming a part of this specification and wherein like numerals of reference will be employed for designating like parts throughout the different views of the drawings, in which:

Figure 1 is a front elevation of a roll polisher in accordance with this invention mounted in position on the housings of a mill, the housings being shown in dotted lines. Fig. 2 is a top plan of the same. Fig. 3 is an enlarged cross sectional view of the polisher taken on the line 3—3 of Fig. 4. Fig. 4 is an enlarged front view of the polishing block holder, the presser bar and feed screw being broken away at both ends. Fig. 5 is a transverse vertical sectional view of the polisher showing the tensioning means for one end of the presser bar in side elevation, and Fig. 6 is a detail plan and 55 sectional view showing one of the supporting brackets for the presser bar.

Our polishing device is adapted to be attached to the housings of a rolling mill in such manner that a polishing block, stone or wheel carried thereby may be moved into engagement with the rolls at any desired time to polish the latter as they revolve. It will be understood that a polisher is provided for each roll and that while we have shown but a single polisher, each roll of the mill is to be similarly equipped, and that the polishers for two or more rolls of a mill may be operated independently or in unison.

The roll housings are indicated at 13, the roll 12 being journaled therein in the usual manner. Secured to each housing 13 is a substantially Z-shaped bracket 6, the inwardly-extending legs of which are apertured to receive lever rods 5 that are suitably connected at their inner ends to a presser bar 3. As herein shown, this presser bar is T-shape in cross section as such form of bar provides convenient means for supporting the polishing block holder and also constitutes a track or guide for such holder during its travel. The lever rods 5 are each provided with a shoulder 20 and arranged on the rods between these shoulders and the inwardly-extending legs of the brackets 6 are springs 8, the function of which is to yieldingly hold the polishing block against the roll during operation of the polisher. The outer ends of the lever rods have pivotally-connected thereto, the bifurcated ends 90 of handles 7, each provided with cams 7', which, when the handles are swung on their pivots so as to depend from the rods 5, are brought into engagement with the brackets 6 and draw the rods 5 outwardly moving 95 the polishing block or stone away from the roll, placing the springs 8 under compression. It will be understood that when the handles 7 are in the position shown in Fig. 5 of the drawings, or when they are moved 100 into alignment with the rods 5, that the springs 8 are exerting their tension to yieldingly hold the polishing block or stone against the roll.

The polishing block 9 is carried in a holder 1 provided on its outer face, along the upper and lower edges respectively, with flanges 27 the upper flange curving downwardly, and the lower flange curving upwardly to receive and hold the presser bar 3, which 110 bar constitutes a track upon which the holder travels when the polisher is operating. The

holder is open at both the outer and inner faces, the polishing block or stone 9 protruding from the open inner face. Journaled in the holder so as to project partially beyond the open rear face thereof is one or more rollers 16 which travel on the inner face of the presser bar 3 and facilitate the travel of the holder on said bar.

The polishing block or stone is inserted 10 in the holder through the open upper side of the latter, and is retained therein by a slide plate 29, the edges of which are received in angle flanges 29' carried by the holder, said plate being secured in position 15 in any suitable manner, as by a spring 30 secured to the upper flange 27 and having a bowed portion which normally lies in back of the plate 29. The holder and plate are somewhat tapering in form, and it will be 20 evident that by depressing the bowed portion of the spring 30 the plate may be withdrawn, and a new polishing block or stone placed in the holder.

The holder 1 has a depending arm 1' provided near its lower end with an eye 1" through which the feed screw 2 extends, the grooves 18 of which screw are of continuous form in both directions in order that when the holder travels to one end of the screw it 30 is automatically returned to the other end, the travel of the holder from one end of the screw to the other and then back again being continuous as long as the screw is operated. A boss 28' formed integral with the lower

35 face of the eye 1" has a bore which receives a pin member that engages in the grooves 18 of the screw 2 and causes travel of the holder along the screw as the latter is operated. This pin member comprises a body 40 17 loose in the bore of the boss 28' and provided on its upper face with a stem 17" which engages in the grooves 18 and which we generally make of substantially elliptical form in plan or cross section. On its lower 45 face the body 17 carries a stem 17" received in a hollow plug 28 threaded into the lower end of the bore in the boss 28'; this plug forms a support or seat for the pin member.

The journals 11 of the screw 2 are mounted 50 in the housings 13 and are connected to the ends of the screws by universal joints 10, the function of which is to prevent any strain being placed upon the screw should the housings move or jump as frequently occurs.

It will be understood that one or the other of the journals 11 is extended through its housing, and driven in any suitable manner.

Such being the construction and arrangement, the operation is as follows:—The 55 screw 2 being driven, the holder 1 is caused to traverse the screw back and forth (by

reason of the screw being of the return form) and with the handles 7 in the position shown in Figs. 1, 2 and 5, the springs 8 are exerting their tension on the presser bar, 65 and yieldingly holding the polishing block or stone in engagement with the roll 12 during the travel of the holder, the device being so located that the screw is above the roll pass so that polishing may be done without 70 interfering with the rolling operation when desired. When the polisher is not in use, the handles are swung down so that the cams 7' pull outward on the rods 5 and presser bar 3, the brackets 4 of the latter 75 swinging on the screw 2, thus moving the polishing block or stone away from and out of contact with the roll 12. In this inactive position of the polishing block or stone, it will of course be understood that the driving 80 of the screw is discontinued until such time as it is again desired to operate the polisher. It will be observed more clearly by reference to Fig. 5 that the disposition or arrangement of the presser bar 3 is such that the 85 holder 1 will travel thereon with comparatively little friction, especially where the holder is provided with the rollers 16.

While we have herein illustrated and described the preferable embodiment of the 90 invention as the same has been practiced by us, yet it will be evident that various changes may be made in the details of construction without departing from the spirit of the invention.

What we claim is:—

1. In a roll polisher, a revoluble feed screw, a pair of lever rods mounted for movement toward and away from the roll, a presser bar carried by said lever rods, a 100 polishing block holder mounted to travel on said bar and having an eye receiving said feed screw, means for causing the holder to traverse the presser bar as the screw is operated, and means for yieldingly forcing the 105 presser bar and holder toward the roll during the polishing operation.

2. In a roll polisher, a revoluble return feed screw, a suitably-supported presser bar, a polishing block holder mounted to travel on said presser bar, means carried by the holder and engaging the screw to cause travel of the holder on the bar as the screw is rotated, and means for yieldingly holding the block carried by said holder against the 115 roll being polished.
